230,601

BADGE READER

Raymond G. Cross, Boynton Beach, and Myron F. Davis
and Walter Furlani, Boca Raton, Fla., assignors to
International Business Machines Corporation, Armonk,
N.Y.

Filed Mar. 7, 1972, Ser. No. 232,646

Term of patent 14 years

Int. Cl. D14—02

U.S. Cl. D26—5 C

FIG. 1

FIG. 2

FIG. 3

FIG. 4

FIG. 1 is a front perspective view of a badge reader showing our new design;

FIG. 2 is a rear perspective view thereof;

FIG. 3 is a front elevational view thereof; and

FIG. 4 is a rear elevational view thereof.

The fragmentary broken line representation of a support panel in FIGS. 1 and 2 is for purposes of illustration only.

What is claimed is:

The ornamental design for a badge reader, as shown and described.
